UNITED STATES PATENT OFFICE.

THOMAS ALBERT BRIGGS CARVER, OF GLASGOW, SCOTLAND, ASSIGNOR TO TEXTILE APPLIANCES LIMITED, OF GLASGOW, SCOTLAND.

STOPPING MECHANISM FOR LOOMS.

No. 911,378.

Specification of Letters Patent.

Patented Feb. 2, 1909.

Application filed February 10, 1908. Serial No. 415,261.

To all whom it may concern:

Be it known that I, THOMAS ALBERT BRIGGS CARVER, a subject of the King of Great Britain, residing at 118 Napierhall 5 street, Glasgow, Scotland, engineer, have invented certain new and useful Improvements in Stopping Mechanism for Looms, of which the following is a specification.

This invention relates to apparatus by 10 which the stoppage of a loom is effected upon any occurrence to the normal working, such as the breakage of a warp thread or of the weft, or upon any other occurrence which might render the stoppage of the loom necessary or desirable, and which through any of 15 the well-known forms of detectors effects the closing of an electric circuit, and consists essentially in an electromagnetic detent apparatus which is included in or controlled by 20 such electric circuit and is particularly designed to be applied to existing looms without alteration of their working parts as usually constructed. Accordingly, by the present invention the coil and the armature of an 25 electromagnet are connected with the ordinary lever controlling the position, in its stepped slot, of the starting handle or shipper lever, preferably by being simply mounted upon the bar which carries the weft fork, and 30 one or other correlated with a reciprocating part of the loom, such as the hammer or the reciprocating lathe, in such manner that during normal working one part can be displaced with respect to the other by the movement of 35 the said reciprocating part, but when the electromagnet is sufficiently energized both parts and with them the lever with which they are connected, are displaced by such movement and caused to disengage the driving mechanism and so stop the loom.

One form in which the improved detent apparatus may be constructed is illustrated in the perspective view of Figure 1 in the accompanying drawings, Figs. 2 and 3 being 45 similar views of slightly modified constructions, and Fig. 4 a longitudinal sectional view on an enlarged scale, showing a preferred construction of electromagnet.

As therein shown, *a* is the ordinary bar 50 which carries the weft fork *b* pivotally mounted at one end thereof, *c* is the bell crank hammer which actuates the weft fork and which is driven, through the arm *d* from the cam *e* on the lower shaft *f* of the loom, and *g* is the

pivoted lever which is actuated by the bar *a* 55 to stop the loom by displacing the shipper lever *h* into the elongated slot *i*. All these parts are as commonly arranged in looms.

According to the present invention the electromagnet *j* of the detent apparatus is 60 secured, preferably adjustably on the bar *a* and the armature *k* is mounted to be moved freely longitudinally of the bar *a* by the hammer *c* (Fig. 1) or by the reciprocating lathe *o* (Figs. 2, 3) on its forward stroke so long as 65 the magnet *j* is not energized; when, however, the electric circuit which includes the magnet is closed by an occurrence to the normal working, the armature *k* will be clamped magnetically to the bar *a* and the latter will 70 therefore be moved on the forward stroke of the hammer or lathe to displace the shipper lever *h* from driving engagement and the loom will stop.

The electromagnet *j* is preferably, but by 75 no means necessarily, constructed as shown of a cylinder of iron which is formed with an annulus to receive the energizing coil *j'* and is bored to receive the spindle *k'* of the spring-returned iron plate or cap armature 80 *k*. The spindle extends rearwardly through the magnet core and in the construction of Fig. 1 is secured, preferably adjustably, to a block *m* which is mounted to slide along the bar *a* and engages the hammer *c* either directly or through an adjustable finger *m'*. A spring *n* is provided to return the armature 85 and its spindle to the position in which they are shown in Fig. 4.

In the modified construction of Fig. 2, 90 the armature spindle extends rearwardly to a distance sufficient to cause it to be displaced forwardly during the latter part of the forward stroke of the lathe *o* by the engagement of the end of the spindle with a 95 plate *o'* suitably secured in any convenient position on the lathe.

Alternately, and in some respects preferably, since it obviates the suddenness of the action, the spindle *k'* may be actuated as 100 shown in Fig. 3 by engagement with a lever *p* fulcrumed at its upper end in a bracket *q*, which would usually be fixed, but may in certain instances be formed integral with or secured to the magnet *j*, and driven by a 105 link *r* connecting it with any suitable point of the lathe. By suitably proportioning the parts, the action is spread over the full

forward stroke of the lathe, or of whatever other reciprocating part from which it may be found convenient to derive the motion.

Having thus described the nature of this invention and the best means I know of carrying the same into practical effect, I claim:

1. In apparatus of the character herein described, a starting handle and means for shifting the starting handle into an inoperative position, said means being controlled by an electro-magnet having one member mounted to move in an axial direction relatively to the other under the action of a reciprocating part of the loom mechanism when the magnet is normally deenergized, substantially as described.

2. In apparatus of the character herein described, a starting handle, means for shifting the starting handle into an inoperative position, an electro-magnet mounted to move with said shifting means, an armature for said magnet mounted to reciprocate under the action of the loom mechanism and adapted to be clamped to said electro-magnet when energized by an occurrence to the normal working of the apparatus, whereby the magnet and the armature are moved together to displace the starting handle, substantially as described.

3. In apparatus of the character herein described, a lever controlling the position of the starting handle of the loom, an electro-magnet and an armature therefor of which one member is connected with the said lever, while the other is free to move in an axial direction relatively to the said member

under the action of any suitable reciprocating part of the loom mechanism when the electro-magnet is normally deenergized, substantially as described.

4. In apparatus of the character described, a lever controlling the position of the starting handle of the loom, a bar carrying the weft fork connected with said lever, an electro-magnet and an armature therefor of which one is clamped to the said bar while the other is mounted to move in an axial direction relatively to the other under the action of a reciprocating part of the loom mechanism, when the electro-magnet is normally deenergized, substantially as described.

5. In apparatus of the character described, a starting handle, a lever controlling the position thereof, a bar carrying the weft fork connected with said lever, an electro-magnet clamped to said bar and normally deenergized, an armature mounted to move freely to and fro with respect to said electro-magnet, means actuated by a reciprocating part of the loom mechanism to move said armature in a direction away from the magnet, said armature adapted to be clamped magnetically to the magnet when energized and to be moved together with the magnet in the aforesaid direction, substantially as described.

In testimony whereof I have signed my name to this specification in the presence of two subscribing witnesses.

THOMAS ALBERT BRIGGS CARVER.
